UNITED STATES PATENT OFFICE.

JOHN N. LUGER, OF MINNEAPOLIS, MINNESOTA, ASSIGNEE TO ST. PAUL TABLE COMPANY, OF NORTH ST. PAUL, MINNESOTA, A CORPORATION OF MINNESOTA.

FOLDING TABLE.

Application filed August 9, 1924. Serial No. 731,214.

My present invention relates to folding tables intended for general use but especially adapted for use in hotel dining rooms and the like, wherein the number of tables used from day to day varies considerably thus making it necessary to move the tables to and from a storage space.

The primary object of the invention is to provide such a table that, while extremely simple and of comparatively small cost to manufacture, is very rigid and easy to set up or take down. Said invention further provides such a table in which all of the movable parts may be folded and secured, concealed within a depending apron on the top of the table. A plurality of such tables may be stacked, the one upon the other, in very compact form so as to occupy a minimum amount of storage space, and when thus stacked the apron of one table will rest directly on the top of an underlying table.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the table turned onto one of its sides;

Fig. 2 is a transverse vertical section;

Fig. 3 is a longitudinal vertical section showing the table folded; and.

Fig. 4 is a fragmentary detail view in bottom plan, showing one of the leg-holding brackets.

The numeral 5 indicates a rectangular table top having a depending endless apron 6 which follows the marginal edge portion of the table top but is inset therefrom. Extending parallel to each end section of the apron 6 and secured to the side sections thereof is a transverse depending supplemental apron 7. At each end of the table top 5 is a pair of legs 8 rigidly connected by upper and lower rails 9 and 10, respectively, and which rails are secured to the intermediate portions of the opposing faces of the legs 8 of each pair. The pairs of legs 8 are hinged at 11 to the under side of the table top 5, inward of the supplemental apron sections 7, for inward folding movement 55 toward each other, and when the table is

set up said pairs of legs engage the supplemental apron sections as stops to position said legs in perpendicular positions and hold the same against outward tilting movement.

To hold the pairs of legs 8 pressed outward against the supplemental apron sections 7, there is provided for each pair of said legs a bracket 12 in the form of the numeral 7. The outer ends of the horizontal and oblique arms of the brackets 12 are hinged at 13 to the intermediate portions of the inner faces of the top and bottom rails 9 and 10, respectively. When the table is set up the brackets 12 extend at right angles to the rails 9 and 10 and it will be noted that the distance between the legs of each pair is less than the distance between the two side sections of the apron 6, and that the two pairs of legs are offset from each other transversely of the table so that, when folded, the free end portions of the legs will extend past each other. It will also be noted that the brackets 12, when the table is set up, are laterally offset from each other and in respect to the transverse center of the table. These brackets 12 are arranged to be folded in opposite directions upon the rails 9 and 10 and each bracket, when folded, is entirely within the plane of the respective pair of legs 8. When the table is set up, the brackets 12 extend at right angles to the rails 9 and 10 and engage the table top as a base of resistance.

To position the brackets 12 and securely hold the same when the table is set up and thereby firmly hold the pair of legs 8 pressed against the apron sections 7, there is secured to the under side of the table top 5 a pair of blocks 14 having in their outer sides open seats 15 into which the rear end portions of the vertical arms of said brackets extend. It will be noted that the rear ends of the vertical arms of the brackets 12 are oblique and extend in the same planes as the rear edges of the oblique arms of said brackets and the respective portions of the seats 15 are correspondingly formed and thereby securely hold said brackets against movement away from the table top while said top holds the brackets against upward movement, thus securely holding the pairs of legs against vertical angular movement in respect to the table top. These blocks 14 also hold the brackets 12 against movement 105 110

in the direction of the folding movement of the pairs of legs 8 and firmly hold said pairs of legs pressed against the supplemental apron sections 7.

5 To hold the brackets 12 against swinging movement out of the seats 15, there is secured to each block 14 a turn button 16 which may be turned into overlapping engagement with vertical arms of the brackets 12 as shown in Figs. 1 and 4.

To fold the table, it is only necessary to operate the turn buttons 16 to release the brackets 12 from the blocks 14 and swing said brackets out of their seats 15 and onto 15 the rails 9 and 10. The pairs of legs 8 may then be folded onto the underside of the table top 5. To hold the legs 6 folded, which in turn hold the brackets 12 folded there is provided a lock bar 17 intermediately 20 pivoted at 18 to a block 19 secured to the underside of the table top 5 and which lock bar is arranged to overlap the rails 10 with a slight springing action and thereby securely hold the movable parts of the 25 table folded as shown in Fig. 3.

To set up the table it is only necessary to swing the lock bar 17 into an inoperative position, to release the two pairs of legs 8 and then swing said legs outward and there- 30 after swing the brackets 12 at right angles to the pairs of legs 8 to cause the same to enter the seats 15, and finally operate the turn buttons 16 to hold said brackets in said seats.

35 It will be noted by reference to Fig. 3 that when the table is folded, the movable parts are within the apron 6 so that a multiplicity of said tables may be stacked, the one upon the other, without engaging any 40 of said movable parts.

The above described table has been put into commercial use and proven highly efficient for the purpose had in view. The peculiar arrangement of the apron sections 7, 45 pair of legs 8, brackets 12 and the blocks 14 produces a very rigid and efficient means for supporting the table top.

50 While the invention, as shown, is embodied in a rectangular table, it is of course understood that it is equally well adapted for use on round tables.

What I claim is:

1. A folding table comprising a table top having a depending apron and transverse depending supplemental apron sections within said apron, legs hinged to the table top inward of said apron sections and engaging said apron sections as stops, upper 55

and lower rails connecting the legs in pairs, 60 a bracket hinged to the rails of each pair of legs for folding movement thereon, a pair of blocks secured to the under side of the table top and having in one of their sides open seats in which the free portions of the 65 brackets are mounted, and from which seats said brackets are released during their fold- ing movement, fastening devices for holding the brackets in said seats, said brackets re- acting against the table top as a base of re- 70 sistance to hold the pairs of legs pressed against the said apron sections, said seats being arranged to hold the bracket against endwise movement in the direction of the 75 folding movement of the pairs of legs and against downward movement away from the table top, and a fastening device for holding the pairs of legs folded under the 80 table top with the brackets between the rails and the table top, said brackets being in the form of the numeral 7 and having the free 85 ends of their horizontal and oblique arms hinged to the rails, said horizontal arms having oblique interlocking engagement with the seats for holding said brackets against downward movement away from the table top.

2. A folding table comprising a table top, pairs of legs hinged to the table top for inward folding movement onto the under 90 side thereof, stops for holding the pairs of legs against outward folding movement, upper and lower rails connecting the legs of each pair, brackets comprising horizontal 95 members hinged to the upper rails and oblique members having their upper ends rigidly secured to the free ends of the horizontal members and their lower ends hinged to the lower rails, said brackets engaging the 100 table top as a base of resistance and ar- ranged to be folded onto said rails by swing- 105 ing movement parallel to the table top, blocks secured to the under side of the table top and having in one of their vertical sides open seats in which the free end por- 110 tions of the brackets are seated during the horizontal swinging movement parallel to the table top, said brackets and blocks hav- 115 ing such interlocking engagement as to hold the brackets against endwise movement in the direction of the folding movement of the pairs of legs and against downward move- ment away from the table top, and fasten- ing devices for holding the brackets in their seats.

In testimony whereof I affix my signature.
JOHN N. LUGER.
